ALBERT GLIDIE, OF NEW YORK, N. Y.

ROTARY ENGINE.

No. 847,761.

Specification of Letters Patent.

Patented March 19, 1907.

Application filed December 26, 1906. Serial No. 349,502.

To all whom it may concern:

Be it known that I, ALBERT GLIDIE, a subject of the King of Norway, and a resident of the city of New York, borough of Manhattan, in the county and State of New York, have invented a new and Improved 5 Rotary Engine, of which the following is a full, clear, and exact description.

This invention relates to certain improvements in rotary engines adapted to be operated by steam, compressed air, or other fluid under pressure; and the object of the invention is to provide certain improvements in the means for controlling the admission and 15 exhaust of said motive fluid in order to gain the maximum efficiency.

The invention consists in certain features of construction and combination of parts, all of which will be fully set forth hereinafter 20 and particularly pointed out in the claims.

Reference is to be had to the accompanying drawings, forming a part of this specification, in which similar characters of reference indicate corresponding parts in all the figures, in which—

Figure 1 is an end elevation of the engine, a portion thereof being broken away. Fig. 2 is a side elevation, a portion thereof being broken away to show the throttle-valve. 30 Fig. 3 is a detail showing the piston, abutment, and inlet and exhaust ports. Fig. 4 is an end elevation, the valve being removed and the valve-chamber being shown in section. Fig. 5 is a plan view of the complete 35 engine. Fig. 6 is a transverse section taken on a plane through the controlling-valve. Fig. 7 is a plan view of a portion of the device, the superstructure being removed. Fig. 8 is a detail showing the eccentric for operating the abutment. Fig. 9 is a detail showing the reverse side of the 40 parts illustrated in Fig. 8. Fig. 10 illustrates details of the valve-operating mechanism, and Fig. 11 illustrates details of the 45 abutment.

In the specific embodiment of my invention which I have illustrated in the drawings I employ a casing made up of two parts 10 and 11, bolted together and having an annular chamber 12, circular in cross-section, formed within the casing. The casing is supported by suitable standards 13, resting upon a base 14, and the standards are provided with journal-boxes 15 for supporting the 50 main shaft 16. This shaft extends through the casing centrally of the annular chamber,

and rigidly mounted upon the shaft is a plate or wheel 17, having its outer circumferential edge 18 extending through a slot in the inner wall of the annular chamber or cylinder 12 60 and serving to close the latter. In order to provide a perfectly-tight joint, the wheel 17 is provided with annular flanges 19, spaced a short distance from the inner surface of the casing, and intermediate these flanges and 65 the casing is provided a packing held in place by the annular packing-rings 20, supported upon the cylinder, as shown in Fig. 2.

As previously stated, the chamber or cylinder 12 is circular in cross-section, and the 70 wheel 17 extends through the casing to the inner side of the chamber. Within the chamber and rigidly secured to the wheel 17 is a circular piston 21, completely closing the annular cylinder and adapted to move through said 75 cylinder and cause the rotation of the wheel 17. This piston may be of any suitable character, but is preferably composed of a plurality of layers rigidly bolted together, one of said layers being integral with or rigidly secured to the wheel 17. In order to cause the movement of the piston 21 within the cylinder 12, I provide suitable inlet and exhaust 80 ports for the motive fluid and a suitable valve for controlling said ports. 85

Preferably the section 10 of the main casing is provided with an extension 22 integral therewith, and within this extension is provided a cylindrical valve-chamber 23, directly above the main shaft 16. Within this valve-chamber 90 is located a valve 24, the shape of which is more clearly shown in Fig. 7, and which has a passage 25 extending therethrough intermediate the two side walls 26 26. The valve is supported upon a valve- 95 stem 27, leading through a packing in the lower side of the valve-chamber, and said valve-stem terminates in an eccentric-strap 28, surrounding and adapted to be operated by an eccentric 29 on the shaft 16. The 100 valve-chamber 23 is provided with an inlet pipe or conduit 30 and an outlet pipe or conduit 31, while the opposite side of the valve-chamber is provided with a plurality of openings leading into the chamber or cylinder 12. 105 As shown in Fig. 3, these passages are four in number, two of them, 32 32, leading into the chamber or cylinder 12 at one side of the abutment, hereinafter referred to, and the other two, 33 33, leading into the cylinder or 110 chamber at the opposite side of the abutment. The passage 25 through the valve 24

is of considerably greater width at one side than at the other and is so formed that when rotated through a portion of a revolution the larger side of said passage remains at all times in communication with the inlet-pipe 30, while the smaller end of the passage may be brought in communication with the ports 33. As the valve does not completely fill the valve-casing, two longitudinal passages are formed extending the entire length of the valve-casing, and both passages communicate at all times with the outlet-pipe 31 below the valve. When the valve is rotated to bring the passage 25 in communication with one of the sets of ports, the other ports will communicate with one of these two longitudinal passages and be in free communication with the outlet-pipe. By reciprocating the valve within the valve-chamber the wall of the valve may be moved across the end of the inlet-pipe 30 and completely shut off the supply, although without interfering in any way with the exhaust-passages. During the normal operation of the engine the valve is moved up and down in its casing once during each revolution of the drive-shaft 16 and of the piston 21. The valve is only rotated when it is desired to reverse the direction of rotation.

In order to cause the reciprocation of the valve within the valve-casing, I provide the eccentric illustrated in Fig. 10. This eccentric is made up of three disks rigidly secured together or formed integral. One of these disks is round and is concentrically mounted upon the shaft 16, while secured to one side of this disk is a second or larger disk 34, having a notch 35 cut in its surface adjacent one side thereof. Upon the opposite side of the first-mentioned disk is a third disk 36, having a lug 37 diametrically opposed to the notch 35 of the disk 34. The valve-stem 27 carries the eccentric-strap 28, surrounding the circular disk, and extending upward from the surface of this eccentric-strap are two projections 39 and 40, extending in opposite directions and having cam-surfaces. The point of the projection 39 normally travels upon the surface of the disk 34, while the point of the projection 40 normally travels upon the surface of the disk 36, and the valve stem 27 is held from rotating. As the projection 37 strikes the cam-surface of the projection 40 the rod and eccentric-strap 28 are moved longitudinally and the projection 39 enters the notch 35 in the disk 34. The opening in the strap 28 is of substantially the same diameter as the circular disk of the eccentric, but is of sufficient length to permit of the longitudinal movement of the strap as the projection 37 strikes the cam-surface of the projection 40. It will thus be noted that the valve-stem is held stationary throughout the greater portion of the revolution of the shaft 16, but is suddenly raised and again lowered

once during each revolution. By means of the improved eccentric above described all side movement of the valve-stem 27 is prevented and the valve is positively operated at the required instant.

At the upper side of the cylinder-casing, intermediate the valve-ports 32 and 33, is located an abutment 41, capable of longitudinal movement and adapted to completely close the cylinder or chamber 12 at this point. Upon the upper side of the casing is also provided means for guiding the abutment in its longitudinal movement, and this means preferably comprises a casing 42, having a packing 43 at its upper end and through which the rod 44, carrying the abutment, reciprocates. The casing 42 rigidly supports an arm 45, having a lever 46 pivoted to the upper end thereof, and this lever is connected to the rod 44 in such a manner that when the lever 46 is raised a simultaneous movement of the rod 44 is effected.

Upon the shaft 16 I provide a second but larger eccentric 47, similar to the eccentric 29, save as to size. The disk 36^a carries a projection 37^a, adapted to engage with the cam-surface of the projection 40^a on the eccentric-strap 28^a, and the largest disk 34^a is provided with a notch 35^a, into which passes the projection 38^a of the eccentric-strap 48 when the rod 48 is moved longitudinally thereby. The two eccentrics are so located upon the shaft in respect to the position of the piston 21 that the abutment 41 will remain in the position indicated in Fig. 2—namely, closing the chamber 12—and the valve will remain in the position indicated—namely, permitting the motive fluid to enter the pipe 30 and pass through the passages 32 in the valve-chamber at one side of the piston, while the exhaust-gases may pass out through the passages 33 and escape through the pipe 31. As the piston 21 nearly completes its revolution, or, in other words, approaches the abutment 41, the eccentric 47 operates to move the rod 48 and simultaneously the rod 44 to lift the abutment out of the chamber or cylinder 12 to permit the passage of the piston 21. Simultaneously the valve 24 is dropped to close the inlet-port, and the inertia of the piston is sufficient to carry it past the abutment to a position beyond the ports 32. At this instant the abutment is dropped to close the chamber and the valve is opened to permit the entrance of motive fluid intermediate the abutment and the piston to cause the further rotation of the latter.

In order to reverse the engine, means are provided for rotating the valve 24, and this means preferably comprises a rod 49, secured to the valve 24 and extending up through a packing in the upper side of the valve-casing. This rod is provided with a lever-arm 50, connected by a link 51 to a lever-arm 52 on a

rotatably-mounted rod 53. A handle 54 is rigidly secured to this rotatable rod 53, and a guide 55 is secured to the superstructure of the engine to control the movement of the handle 54. With the handle in the position indicated in the drawings the valve will occupy the position illustrated in Fig. 6 and the inlet-pipe 30 communicate with the inlet-ports 32. By moving the handle toward a horizontal position the lever-arm 52 causes the movement of the lever-arm 50 and a rotation of the valve 24 to bring the inlet-pipe 30 in communication with the outlet-ports 33. The motive fluid is then delivered to the opposite side of the abutment 41 and pressure is applied to the opposite side of the piston 21.

The eccentrics for operating the abutment and valve are such that it is entirely immaterial in which direction the engine is operating, as the valve will be closed and the abutment raised when the piston reaches a given distance upon one side of the valve and abutment and will be closed when the piston has passed them to a given distance upon the opposite side. Their operation is reversed by a reversal of the direction of rotation of the engine-piston.

Having thus described my invention, I claim as new and desire to secure by Letters Patent—

1. A rotary engine, comprising a curved chamber provided with a slot, a rotary member having a portion thereof adjacent its circumference entering and closing said slot, a piston carried by said rotary member and movable within said curved chamber, a flange carried by said rotary member and substantially parallel to the wall of the chamber adjacent the slot but spaced from said wall, and a packing intermediate said flange and said wall and in contact with the body of said rotary member.

2. A rotary engine, comprising a curved chamber provided with a slot, a rotary member having a portion thereof adjacent its circumference entering and closing said slot, a piston carried by said rotary member and movable within said curved chamber, a flange carried by said rotary member and substantially parallel to the wall of the chamber adjacent the slot but spaced from said wall, a packing intermediate said flange and said wall, and a packing-ring substantially L-shaped in cross-section carried by the wall of said chamber and adapted to force the

packing into engagement with the body of the rotary member.

3. A rotary engine, comprising a casing having an annular chamber therein, a piston movable in said chamber, an abutment radially movable to close said chamber, said chamber being provided with an inlet-port adjacent one side of the abutment and an outlet-port adjacent the opposite side, means for controlling the inlet-port, comprising a reciprocating valve, means for rotating said valve to reverse the engine, and independent means for simultaneously withdrawing said abutment from the chamber and closing the inlet-port.

4. A rotary engine, comprising a casing having a curved chamber, a main shaft provided with a cam, a piston movable in said chamber, an abutment radially movable to close said chamber, said chamber being provided with an inlet-port adjacent one side of the abutment and an outlet-port adjacent the opposite side, a reciprocating valve for controlling said inlet-port, a valve-stem secured to said valve and in engagement with the cam on the main shaft, whereby said valve may be reciprocated, and a second valve-stem secured to said valve and provided with manually-controlled means for rotating the same, whereby the engine may be reversed.

5. A rotary engine, comprising a curved chamber, a main shaft concentric therewith, a piston carried by said shaft and movable in said chamber, an abutment movable to close said chamber, said chamber having an inlet-port adjacent one side of the abutment and an outlet-port adjacent the opposite side of said abutment, a reciprocating valve for controlling said inlet-port, means for simultaneously moving said abutment and reciprocating the said valve to control the inlet-port, a valve-stem secured to said valve, an arm secured to said valve-stem, a valve-lever, and means connecting said lever to said arm, whereby upon the movement of said lever the valve may be rotated to reverse the engine independent of the normal reciprocating movement of the valve.

In testimony whereof I have signed my name to this specification in the presence of two subscribing witnesses.

ALBERT GLIDIE.
